UNITED STATES PATENT OFFICE.

FRANCIS A. NOLAN, OF ST. PAUL, MINNESOTA.

SHOE-HEEL.

1,290,774.

Specification of Letters Patent.

Patented Jan. 7, 1919.

Application filed November 26, 1915. Serial No. 63,353.

To all whom it may concern:

Be it known that I, FRANCIS A. NOLAN, a citizen of the United States, residing at St. Paul, in the county of Ramsey and State of Minnesota, have invented a new and useful Improvement in Shoe-Heels, of which the following is a specification.

An object of this invention is to provide a resilient shoe heel for permanent attachment to a shoe, wherein the fastening means can be accurately and quickly applied to the coöperating parts for the purpose of securing the heel to the shoe.

It has been customary to employ resilient heels on shoes and to either detachably or permanently secure them to the shoes. More particularly this invention has to do with that class of resilient heels, which are permanently secured to the shoes or a portion of the shoe heels. With previous devices the fastening means and the particular construction of the heel employed have rendered shoe heels of the class stated objectionable due to the fastening means being difficult to secure in place, rendering the same effective only part of the time and the shoe heel not preventing slipping at all times and under all conditions. Prior constructions have also in all instances where the cushion heel is fastened permanently by securing fastening devices through the lower surface of the heel, permitted moisture and dirt to collect in cavities or openings which have been provided in the heel. These objections are entirely overcome by my invention. My invention further provides an efficient cushion heel, which will wear longer and produce more effective results than heretofore.

In the accompanying drawing forming part of this specification, Figure 1 is a side elevation of a detail of a shoe, a portion of the heel thereof being shown in section; Fig. 2 is an end view of my improved resilient heel, a portion thereof being broken away and in section; Fig. 3 is a bottom plan view; Fig. 4 is a top plan view; Fig. 5 is a section of a detail taken on the line X-X of Fig. 4; Fig. 6 is a section taken on the line Y-Y of Fig. 4; Figs. 7 and 8 are sections of details, and Fig. 9 is a top plan of an alternative construction.

In the drawing A indicates a detail of a shoe or boot, it being understood that where the term "shoe" is used throughout this

specification and in the claims following, it is intended to be construed as meaning boots, shoes and any other foot wearing apparel with which resilient heels are adapted for use. The shoe A is shown with a portion 60 of the usual heel, portion 2 secured to the lift in the usual manner. B is my improved resilient heel which is adapted for permanent attachment to the heel portion 2 of the shoe or when desired, it can be permanently 65 secured directly to the lift instead of to the heel portion 2. My improved resilient heel B may be made out of rubber or other suitable resilient material and is molded or otherwise formed in the shape of the usual 70 heel. The body B of the heel is formed with a cavity 3 in the top side thereof adjacent to the lower surface of the heel portion 2. The rim or margin 4 of the heel surrounding the cavity 3 has embedded in 75 its upper portion a plurality of washers 5, which are suitably spaced apart and through which fastening devices such as the nails 6 are driven from the lower side of the resilient heel upwardly into the body of the 80 heel portion 2 of the shoe. Suitable buttresses 15 are formed on the heel B projecting into the cavity 3 to provide material in which the washers 5 are securely embedded to hold the resilient heel securely on the 85 shoe. Each of the washers 5 is dished to form a recess 8 in its surface through the opening 9 of which the shank 10 of the nail or other fastener passes. The recess 8 receives the concave head 11 of the nail, so 90 that the head of the nail will lie flush with the lower side of the washer after the nail has been driven home. By forming the recess in the washer in the manner stated, more wearing material is provided in the body of 95 the heel without wearing the head of the nail and releasing the heel from the shoe. In Figs. 7 and 8, a comparison between the new and old method of construction is illustrated. The recess construction appearing 100 in Fig. 7 illustrates the old method of construction in which the nail head projects from the side of a flat washer which is improved upon by my invention.

Corresponding with the axis of the passage 9 through each washer and located on the lower surface of the resilient heel is a spotting protuberance 12 formed with an indenture 13. In fastening the resilient heel on a shoe, the point of the shank 10 of the 110

5 nail 6 or other fastening means is placed in the indenture 13 and the fastening device then driven through the body of the heel toward its upper side. As a result the 10 fastening device is directed so that as it enters the heel it will pass through a corresponding washer and into the body of the heel portion 2 of the shoe. The wall of the recess 8 which tapers inwardly also acts as 15 a guiding surface to assist in directing the point of the fastener through the passage 20 9. In driving the fastener home, a nail set or other instrument or tool is employed which after the fastener has been driven home is withdrawn from the resilient heel. 25 The body of the resilient heel thereupon closes the opening which has been made by the nail or fastener, thus sealing the heel and preventing any moisture or dirt collecting in 30 its body, which otherwise would occur were an opening provided in the body of the heel through which the nail or fastener is driven. In this manner the heel is rendered more sanitary which is an advantage.

35 The guiding spots formed by the protuberances 12 or other suitable marking means can be of any suitable construction for centering the fastening devices over the respective heel engaging elements formed by the 40 washers 5 or other suitable means. The outer margin of the heel is formed with an upwardly projecting lip 14, due to the upper or heel face of the resilient heel being concave. When the resilient heel is secured 45 with its wear surface outmost upon the shoe, the fastening devices hold the heel with its margin compressed tightly against the shoe-heel or lift, thereby producing a close joint under compression and causing the heel to 50 compress tightly against the surface upon which it is mounted. The cavity 3 also assists in causing the heel to adhere by suction in place.

In the manufacture of shoe heels having 55 my invention, the washers can be placed over smooth unshouldered pins for positioning in the resilient material in the mold whereas if the shoulders 9 are not employed like in prior structures the pins must be shouldered 60 to support the washers deep in the mold and the washers are therefore more likely to be upset and ineffectively positioned than by the use of my invention wherein the shoulders take the place of the shoulders on 65 the pins and do not have objectionable openings in the finished product.

The body of the resilient heel is formed with columns 7 in the cavity 3, which project upwardly and press tightly against the 70 surface 16 which may be of the heel portion or lift upon which the heel is mounted. These columns impressing themselves against the surface 16 of the heel sustain the load in spots or zones, and in turn produce a plurality of friction zones on the lower or wear 75

surface of the heel body to prevent slipping. When desired a single column 17, (see Fig. 9) can be employed instead of a plurality, the same result being accomplished thereby to a more limited extent.

80 In fastening my improved heel on a shoe the nails or other fastening devices employed are driven from the wear surface side of the heel through the body, a nail being placed with its point in each of the indentures 13 of 85 the spotters and driven directly through the heel and the corresponding washer into the heel portion 2 or lift of the shoe as the case may be. After the nails have been driven home, the resilient heel is held tightly compressed upon the shoe. The nails are driven home either by hand or machine, and when the driving devices are withdrawn from the body of the heel the openings made by the 90 nails close and seal automatically, thereby preventing any moisture or dirt accumulating in the heel and producing unsanitary conditions.

95 The washers 5 prevent the nails working through the lift and into the shoe after they have been driven into the heel part and lift. The apex ends of the washers also press against the surface of the heel part or lift as the case may be and prevent the nails from tearing the washers loose from the rubber heel.

100 In accordance with the patent statutes, I have described the principles of operation of my invention, together with the apparatus which I now consider to represent the best embodiment thereof, but I desire to have it understood that the construction shown is only illustrative and that the invention can be carried out by other means and applied to uses other than those above set forth within the scope of the following claims.

105 Having described my invention, what I claim as new and desire to protect by Letters Patent is:

110 1. A heel construction comprising an elastic body to be secured upon a shoe surface and a washer embedded therein, said body having a frusto-conical protuberance upon its surface corresponding with the opening in said washer, whereby a fastener driven through said protuberance into said body will enter said washer.

115 2. A heel construction, comprising, an elastic unperforated body, a washer invisible from the tread surface placed therein and a marker arranged on the lower surface of the heel remote from but indicating the position of the opening in said washer, whereby a fastener driven through said body at a position indicated by said marker will enter said opening in said washer and the opening made by said fastener in entering said body will close after the fastener.

120 3. A heel construction, comprising, an elastic body, and a washer embedded there-

in, said washer being provided with a perforated counter sink in one side and formed with an integral outstanding stop adjacent to said perforation, said body with said washer therein being adapted to be applied to a support and said parts being so constructed and arranged that if a heel fastener

is driven through said washer into said support, the outstanding stop of said washer will press against said support.

In testimony whereof I have signed my name to this specification. ¹⁰

FRANCIS A. NOLAN.
